CLAIM

The ornamental design for an electronic security tag, as shown and described.

DESCRIPTION

FIG. 1 is a perspective view of an electronic security tag, showing our new design;

FIG. 2 is a front view of the electronic security tag;

FIG. 3 is a rear view of the electronic security tag;

FIG. 4 is a left side view of the electronic security tag;

FIG. 5 is a right side view of the electronic security tag;

FIG. 6 is a top view of the electronic security tag;

FIG. 7 is a bottom view of the electronic security tag; and,

FIG. 8 is an enlarged view of portion A in the right side view (FIG. 5).

In the drawings the broken lines in FIG. 5, and FIG. 8 depict the bounds of the detail views and form no part of the claimed design.
